F. A. FREDERICK.
GARBAGE RECEPTACLE.
APPLICATION FILED FEB. 16, 1918.

1,297,823.

Patented Mar. 18, 1919.

Inventor

FRANK A. FREDERICK

By his Attorney

Julius H. Tracy

UNITED STATES PATENT OFFICE.

FRANK A. FREDERICK, OF WEST HOBOKEN, NEW JERSEY.

GARBAGE-RECEPTACLE.

1,297,823.

Specification of Letters Patent. Patented Mar. 18, 1919.

Application filed February 16, 1918. Serial No. 217,480.

To all whom it may concern:

Be it known that I, FRANK A. FREDERICK, a citizen of the United States, and resident of West Hoboken, in the county of Hudson and State of New Jersey, have invented certain new and useful Improvements in Garbage-Receptacles, of which the following is a specification.

This invention relates to improvements in garbage receptacles.

The primary object of this invention is to produce a garbage receptacle which will have a body substantially cylindrical in cross-section provided with a flattened portion at the rear thereof, with a cover conforming to the shape of the upper edge thereof and hinged to the body at a plurality of points along said flattened portion so that a rigid connection between the body and cover will be provided that will stand rough usage; and I also preferably provide coöperating members on said flattened portion and cover for automatically fastening the cover to the body when the cover is swung into open position.

In a more intense aspect, my invention comprises the provision on such a body of stiffening ribs having outwardly extending flanges which will coöperate with similar stiffening ribs on the cover to act as guides for the purpose of bringing the automatic fastening members on the cover and body, respectively into registration with each other.

Other features of novelty will appear from an examination of the drawing and the following analysis of the invention.

In the accompanying drawings, in which similar reference characters designate corresponding parts throughout the several views,

Figure 1 is a vertical section through a receptacle embodying my invention;

Fig. 2 is a rear elevation of the receptacle illustrated in Fig. 1;

Fig. 3 is a top of plan view of the receptacle shown in Figs. 1 and 2;

Fig. 4 is a fragmentary view in vertical section showing the cover in open, latched position; and

Fig. 5 is a fragmentary view in section on the line 5—5 of Fig. 2 showing the cover in open position and illustrating the coöperating guiding flanges on the cover and body.

Referring now to these drawings, 1 indicates a body of a garbage receptacle or the

like which is cylindrical in cross-section, except at the rear portion 2 which is flattened out as illustrated more particularly in Figs. 1, 2 and 5, said flattened portion 2 permitting a cover 3 to be hinged to the body at a plurality of points so as to form a rigid and durable hinge-connection therebetween. The cover 3 is cut away at the rear as shown at 3^a in Fig. 3 to conform to the shape of the body 1 and is, as shown, provided with a depending flange 3^b at its perimeter, which flange is likewise cut away at the section 3^a so as to permit the hinging, without binding, of the cover to the said body.

The cover and body respectively are provided with coöperating means for automatically fastening the cover to the body when it is swung on its hinges into open position. As illustrated, the cover is provided with a fastening member 9 and the flattened section 2 of the body is provided with a spring fastening member 10 adapted to spring over the fastening member 9 on the cover to retain the same in open position during the process of emptying the receptacle, and will thus be prevented from flapping up and down during such emptying process.

In the preferred form of device illustrated, means is provided for guiding the automatic fastening members into registration notwithstanding rough handling, and as shown, two stiffening ribs 5 5^a are disposed vertically and parallel to each other along the flattened portion 2 of the said body and these ribs are provided with outwardly-extending flanges 6 6^a which are adapted to coöperate with similar flanges 7 7^a on ribs 8 8^a on the cover 3 for the purpose of guiding into registration the fastening member 9 on the said cover with the fastening member 10 on the flattened section 2 of the said body 1. Other stiffening ribs 4 may also, if desired, be provided.

Any suitable means for providing a rigid and durable hinge connection between the cover and said flattened section may be employed. As illustrated in the preferred form of my invention shown in the drawing, the cover 3 is so hinged by the formation of knuckles 11 11^a on the stiffening members 8 8^a of the cover and the formation of complementary knuckles 12 12^a on the stiffening members 6 6^a of the flattened body section, a pintle 13 being inserted within and coöperating with said integral knuckles to provide rigid and durable hinges and a con-

nection which will withstand rough usage or handling.

The operation of the device will be obvious from the above description.

5 I claim—

1. A garbage receptacle embodying a barrel body substantially cylindrical in cross-section provided with a round bottom and a flattened portion extending from a point 10 above said bottom to the rim thereof, a cover substantially round in conformation having a flattened portion registering with the flattened portion of the body, and a plurality of butt hinges connecting said cover and body 15 located at said flattened portions.
2. A garbage receptacle embodying a barrel body substantially cylindrical in cross-section provided with a round bottom and a flattened portion extending from a point 20 above said bottom to the rim thereof, a cover substantially conforming in shape with said body, a plurality of butt hinges connecting said cover and body located at said flattened portion, and means on the flattened portion 25 of the body for automatically fastening the cover against said body when the same is swung into open position.
3. A garbage receptacle embodying a barrel body substantially cylindrical in cross-30 section provided with a round bottom and a flattened portion extending from a point above said bottom to the rim thereof, a cover substantially conforming in shape with said body, a plurality of butt hinges connecting 35 said cover and body located at said flattened

portion, fastening members on the cover and body respectively for automatically latching the cover to the body when it is swung into open position against the side of said body, and coöperating rib elements on the cover 40 and body for guiding the fastening members into registration.

4. A garbage receptacle embodying a barrel body substantially cylindrical in cross-section provided with a round bottom and a 45 flattened portion extending from a point above said bottom to the rim thereof, a cover substantially conforming in shape with said cross-section of the body, a plurality of butt hinges connecting said cover and body located at said flattened portion, fastening members on the body and cover respectively for automatically latching the cover to the body when it is swung into open position against the side of the body, and angle-iron 50 stiffening members extending transversely on the cover and longitudinally on the body, said members having their outwardly extending flanges adapted to coöperate when the cover is swung into open position to 55 guide the fastening members into registration.

Signed at West Hoboken in the county of Hudson and State of New Jersey this thirty-first day of January A. D. 1918.

FRANK A. FREDERICK.
